Primary Examiner — Michelle E. Wilson*Assistant Examiner* — Richard E Yenchesky(74) Attorney, Agent, or Firm — Maschoff Brennan(57) CLAIM

I claim the ornamental design for a cleansing liquid dispenser, as shown and described.

DESCRIPTION

FIG. 1 is a front view of an embodiment of my design;

FIG. 2 is a rear view thereof;

FIG. 3 is a left view thereof;

FIG. 4 is a right view thereof;

FIG. 5 is a top view thereof; and,

FIG. 6 is a bottom view thereof.

Portions of the cleansing liquid dispenser shown in broken lines form no part of the claimed design.
